PATRICK B. DELANY, OF NEW YORK, N. Y.

ELECTRIC CABLE.

SPECIFICATION forming part of Letters Patent No. 320,229, dated June 16, 1885.

Application filed December 2, 1884. (No model.)

To all whom it may concern:

Be it known that I, PATRICK B. DELANY, of New York city, New York, have invented an Improved Electric Cable, of which the following is a specification.

My invention relates to that class of cables in which a lead or other metallic sheath or pipe is formed around the cable. As is well known, where the lead ingot is heated and then caused to flow round the ordinary cable under comparatively slight pressure the heat of the pipe is liable to burn the insulation of the wire or wires. It is also true that when a cold ingot is used the great pressure required to form the pipe around the cable not only generates heat at the point of flow, but the friction on the cable is liable to tear, break, or injure the covering on the wire or cable, and this liability is increased by the heat generated. For this reason the lead-covered cables of ordinary manufacture are more or less imperfect, and such imperfection results in a more rapid degeneration of the cable in continued use.

The object of the invention is to protect the primary covering on the wire or wires where insulated wire is used, as well as the insulating compound, which is introduced within the pipe in the immediate neighborhood of the conductors in the process of manufacture, from the heat and destructive friction developed in forming the sheath. To accomplish this end I employ, in combination with such a sheath or pipe, a series of insulating-buttons, which are strung on the wire or wires, and which not only constitute an insulating-covering for the wire, but also serve as an armor or shield to protect the wire and the insulation immediately around it during the formation of the sheath.

In Letters Patent of the United States No. 266,353, granted to me October 24, 1882, I have shown a series of abutting, perforated, round-ended, lens-shaped buttons strung on a series of wires. Such buttons may be used under my present invention. In another patent, No. 283,763, granted to me August 28, 1883, I have shown another form of button in connection with spacing-block. Obviously, as presently appears, spacing-blocks may be used where the wire-containing longitudinal recesses are of sufficient depth to protect the

wire from the heat of the sheath, for in that case the block really becomes the equivalent of the button.

55

The insulating-buttons employed by me may of course be made of any suitable material. I prefer, however, to make them of glass, porcelain, earthenware, or other suitable incombustible insulating material, for the insulation of such a cable would remain intact even if in use a heat internal or external should be generated sufficient to burn off the lead sheath. I also prefer not to use spacing-blocks, as above suggested, but to string the perforated insulating-buttons upon the wire or wires, one against the other, so as to form a continuous button-protection or armor for the conductors. It should be noted, also, that the particular shape of the insulating-buttons is immaterial.

In the accompanying drawings, Figure 1 is a sectional view illustrating a portion of a cable having a series of conductors, on which are strung one against the other porcelain insulating-buttons, over which the lead sheath or tube is formed. Fig. 2 is a transverse section of the same. Fig. 3 is a similar view illustrating a cable containing a single conductor, on which perforated insulating-buttons of somewhat different shape are strung; Fig. 4, a view of another section of cable, showing another form of button; Fig. 5, a similar view of another form of cable in which spacing-blocks are used; Fig. 6, a transverse section of the same; and Fig. 7 shows still another form of button.

In all the views A represents a lead or other metallic sheath or pipe which has been formed or flowed around the cable according to any of the well-known ways now in general use.

In Figs. 1 and 2 I have shown lens-shaped buttons B, strung one against the other on a series of wires. These wires may have a primary insulation or may be bare. The space within the pipe around and between the buttons and conductors may be filled with any suitable insulating compound, as illustrated at C in Fig. 4.

In Fig. 3 the buttons B are of a somewhat 100 different shape, and are strung upon a single conductor, which passes centrally through the buttons, which conductor may have a primary insulating covering or not, as may be

BEST AVAILABLE COP

deemed best, and the pipe may be filled with insulating material C, as above mentioned.

It will be perceived that in the cable shown in these figures the wire and its primary insulating-covering, as well as that part of the insulating compound which is immediately around the wire in the eyes or perforations of the buttons, will be protected from the heat developed in putting the sheath over the cable, as well as from the damaging frictional contact with the sheath.

In Fig. 4 I have shown buttons having concave depressions on each side and curved peripheries. Under this organization the insulating compound introduced into the pipe will fill the spaces between the opposite concave faces of the buttons, but will be thoroughly protected from the heat or friction of the sheath.

In Fig. 5 I have shown buttons similar to those illustrated in Fig. 4; but instead of placing them one against the other I have shown interposed spacing-blocks D. These spacing-blocks are formed with radial longitudinal recesses d, within which the conductors are laid. The blocks are preferably of the same diameter as the buttons, and, as will be obvious, the wires will be completely protected. I prefer to employ buttons only, substantially such as illustrated in the other figures, though so far as the principle of the invention is concerned spacing-blocks having recesses of sufficient depth to thoroughly protect the wire constitute buttons.

In Fig. 7 I have shown buttons B, formed on one side with a projecting teat, b, and on the other side with a flat seat, b', against which the teat of the adjoining button rests. It will be observed that while the peripheries of such buttons are not in contact or as close together as the peripheries of the other buttons illustrated, still they serve as an effectual shield to prevent the sheath from injuring the insulation of the wires, because they are really so close together that the lead pipe cannot possibly sink or bend down between them to reach the wires. Insulating compound C may also be used in this form of cable, if desired.

The ordinary lead-pipe machines for forming sheaths around cables are well understood, and need no illustration or description. So far as the insulating compound is concerned, the cable may be drawn through a bath of it before coming to the pipe-forming machine, or the compound may be introduced within the pipe as it is formed around the cable, or may be forced into the pipe in a liquid condition under pressure afterward. These three operations are, however, common, well known, and generally understood, and therefore need no description nor illustration.

All the forms of cable I have described are capable of bending or flexing to permit of their ready handling.

When covered with the lead sheath, the

cable may, therefore, be wound upon a reel for transportation, or handled with the required facility.

Another characteristic of my cable is that the buttons, in addition to the functions above described, also serve as armors to resist the bruising, crushing, or mashing of the cable.

A lead sheath is of such softness that an ordinary cable might be mashed out of shape. In my improved cable, however, the buttons afford a practically continuous support or core for the interior of the cable. The cable is therefore possessed of great strength and durability.

Where several conductors are included in the sheath, the buttons always hold them perfectly separated and at precisely the same distance from each other and from the sheath, no matter how much pressure may be exerted on the buttons, and of course where a single conductor is used, as in Fig. 3, it is always held in the axial line of the tubular sheath. For these reasons, which constitute important features of my invention, my improved cable is perfectly uniform in structure.

I am aware that lead coverings have been formed around cables differing in structure from and not possessing the characteristics of my cable. For instance, in the patent of Rogers and Shaw, No. 220,944, a cable made up of twisted wires, each wire being covered with spun glass or asbestos, is shown as having a lead sheath formed around it by an ordinary lead-pipe machine. I therefore make no claim to such subject-matter.

I am also aware that the patent of Manly, No. 231,825, shows conductors passing through apertures in contiguous insulating blocks of wood, such blocks being drawn in or loosely inclosed within a pipe, the space being filled with insulating material; and I do not, therefore, claim such subject-matter.

I claim as my invention—

1. The combination of a conductor or series of conductors, insulating-buttons strung thereon, and a metallic sheath or pipe formed around the cable, as described.

2. The combination, substantially as set forth, of a conductor or series of conductors, a series of abutting incombustible insulating-buttons strung thereon, and a lead sheath formed thereon, as described.

3. The combination, substantially as set forth, of a conductor or series of conductors, a series of abutting incombustible insulating-buttons strung thereon, a metallic sheath formed thereon, as described, and an insulating compound which occupies the space around and between the conductor or conductors and buttons.

In testimony whereof I have hereunto subscribed my name.

P. B. DELANY.
